UNITED STATES PATENT OFFICE.

CHARLES H. BOECK, OF JACKSON, MICHIGAN.

DESIGN FOR AN OIL-STOVE.

SPECIFICATION forming part of Design No. 24,914, dated November 19, 1895.

Application filed July 22, 1895. Serial No. 556,838. Term of patent 7 years.

To all whom it may concern:

Be it known that I, CHARLES H. BOECK, a citizen of the United States, residing at Jackson, in the county of Jackson and State of Michigan, have invented and produced a new, original, and useful Design and Shape or Configuration for an Article of Manufacture—to wit, an Oil-Stove—of which the following is a specification, reference being had to the accompanying drawings, made part hereof, in which—

Figure 1 is a front elevation of a stove, showing my design; and Fig. 2 is an end elevation of the same, viewed from the right in Fig. 1.

Like numerals of reference indicate like parts in both views.

In the drawings, 1 is a supporting-frame, composed of flat strips of steel pressed or stamped into shape and riveted together. This frame, viewed in front elevation, presents two rectangular sections, the section at one end being longer and higher than the section at the other end, so that table or top 2, covering the longer higher section, and the table or top 3, covering the shorter and lower section, present the appearance of two steps in a stair. Within the longer and higher section of the supporting-frame are two vertical cylindrical stove-bodies 4 4, symmetrically spaced in such section, and within the shorter and lower section of the supporting-frame and about centrally thereof is a single vertical cylindrical stove-body 5 of larger diameter than the stove-bodies 4 4. Each of these stove-bodies is preferably somewhat enlarged at top and has doors 6 6 6. The tables or tops 2 3 are provided with grated openings 7 7 7, directly beneath which the stove-bodies 4 4 5 are placed and secured.

In each of the two sections of the frame 40 above referred to is a horizontal pan or shelf 8 8, secured to the frame immediately beneath the lower ends of the stove-bodies 4 4 5, the pan or shelf beneath the single stove-body being nearer the floor than the other pan or 45 shelf. The lower end of each of the stove-bodies is encircled and braced by metal strip 9 9, secured to and extending between the end portions and the middle portion of the supporting-frame.

10 is a horizontal cylindrical tank to the rear of the frame and extending the full length thereof. This tank is suitably connected with and is designed to supply stove 5 with oil.

11 is another horizontal cylindrical tank connected with and designed to supply oil to the stoves 4 4 and resting upon the frame in the rear of the stoves 4 4. This tank is placed higher than the tank 11, and extends only 60 about the length of the section of the frame within which the stoves 4 4 are disposed, the capacity of the two tanks, however, being about the same.

The leading features of my design are the 65 two-section frame, the two-step top or table, the stove-bodies of varying heights and sizes, and the two horizontal cylindrical tanks arranged in relation to the stove-bodies, substantially as shown.

What I claim as my invention, and desire to secure by Letters Patent, is—

The design for an oil stove, substantially as herein shown and described.

CHARLES H. BOECK.

In presence of—

JAMES W. DOW,
U. L. BADGLEY.
